Application filed November 10, 1900. Serial No. 36,125. Term of patent 14 years.

To all whom it may concern:

Be it known that I, CHARLES P. MOSHER, a citizen of the United States, residing in Philadelphia, Pennsylvania, have invented and produced a certain new and original Design for a Sad-Iron Handle, of which the following is a specification.

My design for a sad-iron handle is clearly illustrated in the accompanying drawing, which represents the handle in perspective.

The essential feature of the design is the handle having ornamental side projections, one on each end of the handle, as shown in the drawing.

15 C is the base of the sad-iron, and C' is the

handhold. Projecting from the side of the handle at each end are arms c c, which terminate in circular portions C', giving the effect clearly shown in the drawing.

I claim—

20 The design for a sad-iron handle as herein described and as illustrated in the accompanying drawing.

In testimony whereof I have signed my name to this specification in the presence of 25 two subscribing witnesses.
